(57) **CLAIM**

The ornamental design for a shower valve handle, as shown and described.

DESCRIPTION

FIG. 1 is a perspective view of the shower valve handle showing our new design;

FIG. 2 is a top plan view thereof;

FIG. 3 is a bottom plan view thereof;

FIG. 4 is a side elevational view thereof, the opposite view and views taken 90° from the view of FIG. 4 being the same; and,

FIG. 5 is another side elevational view thereof, taken 45° from the view of FIG. 4, the opposite view and views taken 90° from the view of FIG. 5 being the same.

The broken line showing of the opening in FIG. 3 and the top surface in FIGS. 1 and 2 is for illustrative purposes only and forms no part of the claimed design.
